US00D977480S

(12) **United States Design Patent** (10) Patent No.: **US D977,480 S**
(45) Date of Patent: ** Feb. 7, 2023

(54) **DEVICE FOR ILLUMINATION AND IMAGING OF A TARGET**

(71) Applicant: **Stryker European Operations Limited**, Carrigtwohill (IE)

(72) Inventors: **Gavin Michael Murray**, Vancouver (CA); **Gregory Vincent Browne**, Vancouver (CA); **James Elliott Cameron**, Victoria (CA)

(73) Assignee: **Stryker European Operations Limited**, Carrigtwohill (IE)

(**) Term: **15 Years**

(21) Appl. No.: **29/765,930**

(22) Filed: **Jan. 12, 2021**
